UNITED STATES PATENT OFFICE.

EDMUND B. POWERS, OF BROOKLYN, NEW YORK, ASSIGNOR, BY DIRECT AND MESNE ASSIGNMENTS, TO RAILWAY CAB SIGNAL & EQUIPMENT COMPANY, OF PORTLAND, MAINE, A CORPORATION OF MAINE.

SAFETY DEVICE FOR RAILWAY-SERVICE.

SPECIFICATION forming part of Letters Patent No. 748,649, dated January 5, 1904.

Application filed April 8, 1902. Serial No. 101,880. (No model.)

To all whom it may concern:

Be it known that I, EDMUND B. POWERS, a citizen of the United States, residing in the city of New York, borough of Brooklyn, in the county of Kings and State of New York, have invented a certain new and useful Improvement in Safety Devices for Railway-Service, of which the following is a specification.

10 The invention relates to means for automatically displaying signals in the cab of a moving locomotive for the information of the engineer or other occupant of the cab, and more particularly to means for automatically 15 stopping the train.

The object of the invention is to lessen the danger of collision and other railway accidents by providing means whereby the engineer may be notified by signals within the 20 cab to proceed with caution under certain circumstances and for displaying a danger-signal and also automatically applying the brakes when the conditions are so dangerous as to require an immediate stop. The signals 25 are operated by vanes analogous to the usual semaphore-arms placed near the track at dangerous points and set by switchmen or other track attendants and arranged to be struck by an arm secured to a transversely-arranged 30 shaft carried by the locomotive. The extent of motion imparted to the shaft is governed by the height at which the vane is placed relatively to the height of the arm passing beneath it and correspondingly determines the 35 nature of the signal displayed. As I have carried out the invention the movement of the arm through a short arc in escaping below a vane displays a green light and actuates a whistle in the cab as cautionary signals, and the movement through a longer 40 arc, caused by passing a vane at a lower elevation, displays a red light as a danger-signal and automatically applies the air-brakes.

The invention consists in certain novel arrangements of parts and mechanism by which the above-mentioned objects are attained and also in certain details of construction to be hereinafter described.

The accompanying drawings form a part of

this specification and show a preferred form 50 of the invention.

Figure 1 is an elevation showing the interior of a locomotive-cab equipped with my invention as seen from the rear and also showing the mast or standard on which are 55 mounted the operating-vanes. Certain details of the locomotive equipment not specifically related to the invention are omitted. Fig. 2 is a corresponding vertical section of a portion of the cab, showing the invention in 60 elevation. The remaining figures are on a larger scale and show portions detached. Fig. 3 is a side elevation showing a preferred means for automatically applying the air-brakes. Fig. 4 is a face view of the auto- 65 matically-actuated switch for operating the light-signals by electricity and also shows the manner of connecting from a storage battery or other source of electricity. Fig. 5 is a side view of the whistle-signal mechanism. 70 Fig. 6 is a plan view, partly in horizontal section, showing the attachment of the arm to the shaft.

Similar letters of reference indicate the 75 same parts in all the figures.

A is the boiler of a locomotive, which may be of any ordinary or approved type, and A' is the usual cab over the rear portion. The controlling, indicating, and operating equipments (not shown) for the locomotive may be 80 of the usual or any approved construction, as will be understood.

Transversely of the cab, preferably above the roof, extends a shaft B, mounted in supports or bearings B', in which it is free to 85 turn. The overhung ends are provided with collars B² B³, serving to prevent axial movement, one of which, B³, carries an adjustable arm B⁴ at a right angle to the shaft and standing normally in a vertical position near the 90 edge of the roof, adapted when its free end contacts with an obstruction in its path to be deflected out of the vertical and correspondingly partially rotate the shaft B, the extent of the rotation depending on the angle of deflection of the arm in escaping beneath the obstruction. For the latter I prefer to use a 95 device analogous to a semaphore-signal and

consisting of a vertical mast or standard M of suitable height set firmly alongside the track and carrying strong narrow wings or vanes M' M², pivotally mounted in its upper end 5 and adapted to be operated by wires M³ M⁴ or other suitable connections by a switchman or other attendant through any suitable mechanism, either by hand or automatically. One vane, M', is mounted higher than the other, M², 10 or is arranged to maintain a higher position transversely of the path of the arm B⁴ on the moving locomotive, and thus cause the arm to be deflected, but to a lesser degree in passing beneath it than by the other or lower 15 vane M². Both vanes are adapted to hang idly in pockets in the standard when not required to be set for service, and are thus removed from dangerous proximity to passing trains.

20 On the shaft B at suitable points are a lever B⁵ and finger B⁶, adapted to swing through arcs in unison with the arm B⁴. The lever B⁵ extends downwardly through a longitudinal slot a in the cab-roof and lies adjacent to 25 a switchboard C, across the face of which it is adapted to sweep.

C' is a switch turning on a center C² and contacting successively with points C⁴ C⁵, arranged in an arc about the center, and having a handle C³, by which it may be moved. The switch lies normally on an insulated portion C⁶ of the arc, with the handle C³ in the 30 path of the lever B⁵.

C⁷ and C⁸ are incandescent electric lamps set 35 in the interior of the cab in a location to be plainly seen by the engineer when he is at his post and arranged to be illuminated by a current from a storage battery C⁰, carried on the locomotive and connected, as shown, to the 40 switch C', contact-points C⁴ C⁵, and lamps C⁷ C⁸, as indicated in Fig. 4.

C⁷ may be understood as indicating a green light or cautionary signal, and C⁸ a red light or danger-signal. The former is connected 45 to the first contact-point C⁴ and the latter to the second or outer point C⁵. Thus arranged the action of the upper vane M' upon the arm B⁴ is to force the lever B⁵ partially across the face of the switchboard, carrying with it the 50 switch C', leaving the latter upon the contact-point C⁴ and showing the cautionary signal or green light to the engineer. The act of passing a standard on which the lower vane M² has been set throws the lever farther 55 and moves the switch to the contact-point C⁵ and displays the red light or danger-signal.

It will be seen that by setting the desired vane located at a point at the commencement of a block or at the approach to a switch 60 or other dangerous portion of the road the corresponding signal—either “caution” or “danger”—will be displayed in the cab of any passing locomotive equipped with my invention. In practice I prefer to locate two 65 standards at suitable distance apart near dangerous points on the road and arrange the first to display the green or cautionary

signal and the second to show the red or danger signal.

Two additional signals are employed, operated by the finger B⁶, above referred to. The first is a whistle D, actuated by the lesser movement of the arm B⁴ and serving as an additional cautionary signal. It consists of a whistle operated by compressed air and 75 connected to the pressure side of the air-brake system and held in the closed or inoperative condition by a spring-dog F', engaging a detent F² on the whistle-valve stem F³, in opposition to the force of a spring F⁴, tending to turn the stem and admit air under pressure to the whistle-bell. The dog F' is connected by a chain F⁵ or otherwise to the finger B⁶, which lies normally in an approximately horizontal position and when turned 80 by the partial rotation of the shaft pulls upon the chain and releases the valve-stem, thus providing an audible cautionary signal in conjunction with the visual green-light signal. The whistle-signal is reset by forcing 85 the arm F' against the tension of the spring until the detent is again engaged by the spring-dog. Attached to the same finger is a slightly-longer chain G⁶, connected at the lower end to a spring-catch G', engaging an 90 annular latch or collar G², arranged to slide on the spindle G³ of the air-brake-operating valve G and subject to the expansive force of a helical spring G⁴ inclosing the spindle and abutting at the inner end against the 95 stuffing-box or other fixed portion of the valve-casing. While the catch is in engagement with the collar the spring is of no effect, and the spindle may be moved axially by the brake-lever G⁷, as usual in applying 100 or releasing the air-brakes; but so soon as the arm B⁴ contacts with a low vane M² the increased rise of the finger B⁶ takes up the slack in the chain G⁶ and releases the spring 105 G⁴, which immediately exerts its force to 110 move the air-brake valve in the direction to apply the brakes and bring the train to an immediate stop. The action of the spring G⁴ may be resisted by the engineer through the lever G⁷ if the sudden stop is undesirable; 115 but the pressure exerted by the spring is sufficient to warn the engineer, if his hand be on the lever, in connection with the simultaneously-displayed red light, that danger is imminent, and, if the brake-lever be free, the 120 brakes will be automatically applied.

H H are springs of equal tension, each attached at one end to the lever B⁵ and at the other to convenient points on the cab, and serve to maintain the arm B⁴ in the upright 125 position, while allowing it to be deflected in either direction, as required, by the forward or backward movement of the locomotive. To allow the backward movement without derangement, I prolong the slot a on both 130 sides of the shaft B and also provide a slot, through which the finger B⁶ may descend idly. The arm B⁴ is mounted adjustably in the collar B³ and may be set up or down

therein to produce the required degree of deflection in passing beneath the vanes. It is held in place by the set-screw *b*.

The vanes may be painted green and red, respectively, and serve as additional track-signals for the engineer if they are so situated as to be easily seen. The vanes may be mounted in the standards, with provisions for adjusting them vertically, as will be understood.

Importance is attached to the location of the arm *B*⁴ at the edge of or extending a short distance beyond the cab-roof, for the reason that when so placed it may be operated by vanes not reaching over the roof, and therefore not liable to strike projections on the trains, and also to avoid the danger of accident to trainmen on the roofs of the cars, which is greatly increased by rigid arms or brackets extending across the track near the level of the car-roofs.

By providing both an audible and visible automatic cautionary signal for the engineer the chances of both being unheeded are very remote, and when an immediate stop is necessary to avoid an accident the display of the danger-signal and the effort automatically to apply the brakes cannot occur unnoticed by the engineer unless he be suddenly incapacitated by accident or illness, in which case the brakes will be applied automatically and the train brought to a standstill.

Modifications may be made in the forms and proportions of the parts within wide limits without departing from the principle of the invention or sacrificing its advantages.

The shaft *B* may extend beneath the roof of the cab instead of exterior thereto, as shown, and may be shorter than here represented. I prefer to extend it to both sides of the cab, for the reason that this arrangement allows the arm *B*⁴ to be placed at either side, as may be found necessary or desirable. The height of the standards may be varied to conform to the location of the shaft *B*. The whistle and air-brake locks may be operated by cords or chains wound upon a small drum or cylinder in place of the finger *B*⁶, as will be readily understood, the latter construction offering an advantage in that the descent of the finger through the roof of the cab in running backward will be avoided.

Although I have described the vanes as mounted in pairs in the standards, and prefer this construction, it will be understood that a standard may be erected for each vane, and in some situations the uppermost or "cautionary" vane may be a fixed arm, if preferred, as at drawbridges, crossings, and dangerous switches.

When the conditions are such as to preclude the use of standards alongside the track, as in narrow tunnels or in other situations where space is limited, the automatic action may be induced by vanes arranged to slide vertically and be raised or lowered, as required,

to produce the desired deflection of the arm *B*⁴, or the vanes may be otherwise mounted and operated.

A fixed vane may be located at any desired point to operate the cautionary signals for the purpose of testing their efficiency and condition before approaching a dangerous portion of the track—as, for instance, before entering a tunnel or approaching a railway-terminal having a multiplicity of switches.

Parts of the invention may be used without the whole. The green and red lamps may serve alone or they may be omitted and the whistle and brake-setting devices relied upon alone, or other signals may be substituted for those described.

The construction of the electric switch may be varied, as may also the mechanism for operating the whistle and applying the air-brakes.

More than two sets of signals may be operated by employing additional vanes adapted to cause a third degree of deflection of the arm and actuate additional signal mechanisms.

All the parts and equipments not specifically described will be understood to be of any ordinary or approved construction and arrangement.

That portion of the invention relating to visible or audible signals to the engineer or other occupant of the cab is not claimed in this application, but is made the subject-matter of a separate application, filed March 5, 1903, Serial No. 146,266.

I claim—

1. The combination with a locomotive-cab of a shaft extending transversely thereof, an upwardly-extending arm secured to the shaft and adapted to partially rotate the latter by the deflection of said arm in contacting with an obstruction in its path, a finger carried by said shaft, a brake-controlling mechanism located in said cab, means tending automatically to move said controlling mechanism to apply the brake, and a locking device for such means, and connections from said finger to said locking device whereby a partial revolution of said shaft will release the locking device and move said controlling mechanism in the direction to apply the brake.

2. The combination with a locomotive-cab of a shaft mounted therein, an arm secured to said shaft and adapted to partially rotate the latter by the deflection of said arm in contacting with an obstruction in its path, a finger carried by said shaft, a brake-controlling mechanism, automatic means for moving said controlling mechanism to apply the brake and connections thereto from said shaft, whereby a partial revolution of said shaft will automatically apply the brake.

3. In an apparatus of the character set forth, a shaft mounted in the cab, an arm secured to said shaft and adapted to partially rotate the latter, a finger carried by said shaft, a brake-controlling mechanism and connections

thereto from said shaft, means for automatically moving said controlling mechanism to apply the brake whereby a partial revolution of said shaft will automatically apply the
5 brake, and a vane supported adjacent to the track in the path of said arm adapted to be struck thereby and cause a partial revolution of said shaft.

4. In an apparatus of the character set forth,
10 a vane mounted adjacent to the track and extending transversely of the line of said track, in combination with an arm carried on the cab of a locomotive on said track, arranged to strike said vane and be deflected thereby,
15 a finger carried by said shaft and a brake-operating mechanism on said locomotive, and connections from said arm to said brake-operating mechanism, whereby the contact of said arm and vane will automatically apply
20 the brake.

5. In an apparatus of the character set forth, a support located near the track, a vane mounted thereon and extending transversely of the line of said track, in combination with an arm
25 carried on the cab of a locomotive on said track, arranged to strike said vane and be deflected thereby, and a brake-operating mechanism on said locomotive, a brake-controlling mechanism, means for automatically moving
30 said controlling mechanism to apply the brake and connections from said arm to said brake-operating mechanism, whereby the contact of said arm and vane will automatically apply
the brake.

- 35 6. In an apparatus of the character set forth, a support located near the track, a vane pivotally mounted therein adapted to hang normally vertically therefrom or to be held extended transversely to the line of said track,
40 and means for moving said vane to either of said positions, in combination with an arm carried on the cab of a locomotive on said

track, arranged to strike said vane and be deflected thereby, and a brake-operating mechanism on said locomotive, a finger carried by
45 a shaft rotatably mounted on the cab, brake-controlling mechanism, means tending automatically to move said controlling mechanism to apply the brake and connections from said arm to said brake-operating mechanism,
50 whereby the contact of said arm and vane will automatically apply the brake.

7. An air-brake-operating valve located in the cab of a locomotive, having a valve-stem G³ and operating-lever G⁷, a spring exerting
55 its force in the direction to move said valve-stem to apply the brakes, a catch controlling said spring, connections from said catch to an arm on the exterior of said cab, arranged to be deflected by contact with an obstruction in its path and thereby lift said catch and release said spring.

8. In an apparatus of the character set forth, and air-brake valve having the valve-stem G³ and operating-lever G⁷, a helical spring encircling said stem and abutting against the valve-casing, a tubular collar G² inclosing said stem and receiving the pressure of said spring, a spring-catch G' arranged to engage said collar and restrain said spring while permitting the said stem to move freely within said spring and collar, and connections from said spring-catch whereby it may be withdrawn to release said collar and permit said spring to exert its pressure to move said stem
70 in the direction to apply the brake.

In testimony that I claim the invention above set forth I affix my signature in presence of two witnesses.

EDMUND B. POWERS.
